UNITED STATES PATENT OFFICE.

HENRY W. BRENT, OF BALTIMORE, MARYLAND.

OIL BURNER.

Application filed August 10, 1920. Serial No. 402,607.

To all whom it may concern:

Be it known that I, HENRY W. BRENT, a citizen of the United States, residing at Baltimore, in the State of Maryland, have invented certain new and useful Improvements in Oil Burners, of which the following is a specification.

This invention relates to certain new and useful improvements in burners of oil-stoves, oil-heaters and the like, and it has for a leading object the improvement of the construction of burners of this type and the provision of novel means for the proper adjustment of the wick so as to minimize the danger of fire and maintain the wick, whether visible or invisible, at such position that there will result a desired blue flame under normal working conditions, the arrangement being such that the wick may be adjusted to the right position, to attain the desired result and without necessarily requiring the inspection of the flame and by a simple single movement of an operating mechanism.

The present invention is an improvement of the oil burners disclosed in my former Patents Nos. 1,082,796, dated December 30, 1913; and 1,313,059, dated August 12, 1919, although the salient features of the present invention may be employed with other types of burners without departing from the spirit of my invention.

With the above and other objects in view my invention consists of the parts and the constructions, arrangements, and combinations of parts which I will hereinafter describe and claim.

In the accompanying drawing forming part of this specification and in which similar reference characters indicate like parts in the several views;

Fig. 1 is a side elevation of a burner tube embodying my invention, showing portions broken away.

Fig. 2 is an enlarged horizontal sectional view on the line 2—2 of Fig. 1.

Figs. 3 and 4 are details to be referred to.

In carrying out my invention I may use the present improvements in connection with the different types of burners, either with or without the usual spreader plates, and whether said burners are to be used in connection with oil-stoves, oil-heaters, or like devices; for present illustrative purposes I have shown my improvements as applied to the type of burners disclosed in my aforesaid prior patents. Any suitable flame

spreader, not shown, may be used if desired, in conjunction with my improved type of burner. In the present case, as in the prior patents mentioned, the burner tube, A, is preferably formed with concentric inner and outer walls, 1, 2, joined at the bottom and adapted to enclose between them a circular flat wick A', the space between the inner and outer walls of the burner tube usually forming a font or receiver, to which oil is supplied through a connection a' in the usual manner.

In the construction of the burner tube such as I have specified, the wick usually has its lower end mounted in and carried by a thin metal casing A², whose lower edge is turned up to receive the bottom of the wick. This casing is generally made of perforated sheet metal to allow the oil to have free access to the wick, the perforations being further employed for the reception of the pointed teeth of the usual wick raising wheel which is mounted on a hand operated shaft. Experience has shown, however, that it is extremely difficult with the perforated casing and usual sharp toothed wheel engaging the same, to uniformly or evenly raise and lower the wick, so that the upper edge of the wick is maintained in a true level position.

To secure an even flame, in devices of this character, the wick should be adjusted to come level with the top of the outside burner tube. Sometimes there is a high point or irregularity on the top edge of the wick which can be patted down, with the fingers or otherwise, but often these projections or irregularities are such that the edge of the wick cannot be made smooth by the mere act of patting down so that the wick will be perfectly level all around, and in such cases it is often necessary to remove the wick and turn the same around in the tube until the desired working position is obtained. Even when this is done, it not infrequently appears that the wick does not level-up properly to insure the proper even flame and in such event it is necessary to remove the oil reservoir and to disarrange other parts. Many of the objections noted are due to the fact that the wick is not easily inserted in the burner tube in a true position, and cannot be maintained true even after insertion, and where there is an uneven top edge to the wick, it is impossible to procure the desired blue flame. Experience has shown that much of the unevenness of

the wick is due largely to the employment of the usual sharp-prong wheel and perforated sheet metal wick casing, since in raising the wick by these instrumentalities the wick ⁵ seems to be caused to bind more or less on one side than the other and consequently to be raised and lowered unevenly and with more or less difficulty.

In the present instance I am able to overcome the objections arising from the presence of a crooked wick especially in the oil stove, or where a true wick is of absolute necessity, as an uneven wick will not provide an even flame for baking or broiling; ¹⁰ at the same time the uneven flame produced by the crooked wick is an element of danger and the cause of possible conflagration and injury to persons in the house or apartment. In brief, with the usual pronged ¹⁵ wheel and perforated casing it is impossible to procure a true flame by the insertion into the burner tubes of a perfectly straight wick; in the construction I am about to describe, and where I use a positive rack-and-pinion and a positive grooved guide for the rack-bar, it is next to impossible to obtain anything but an absolutely correct or even flame and a rack-bar operating substantially without friction. ²⁰

It is a well known fact that a straight and true wick often becomes uneven in fitting it into the burner and various suggestions have been offered to the public as a means for correcting this defect, but at best these ²⁵ means involve unclean and tedious operations and produce poor results. It is also well known in the art that it is difficult to insert the wick when using the usual pronged wheel as much pressure is often required to get the entering part of the wick to pass the prongs on the wheel. In my experiments I have found it highly desirable to so fashion the rack-bar and the slotted tube in which it operates with a positive ³⁰ grooved-walled guide so that all danger of the rack binding or being deflected from its true sliding position will be obviated and said rack will be freely and accurately guided in its up and down movements under all working conditions, and the wick ³⁵ will be uniformly raised or positioned so as to maintain a straight and true burning top edge.

The foregoing various objections are cured by the mechanism which I will now describe.

The outer burner tube I fashion with a depressed portion or housing, 3, which has a slot or slots, 4, in an intermediate portion for the passage of the toothed wick operating wheel, 5. Within the recess or channel formed by depressing the tube, is a rack-bar, 6, which bar is secured to the side of the usual thin metal wick-holder, ⁶⁰ A², but the bar is in the form of a positive

rack with teeth or spurs for the proper engagement of the spur teeth of the pinion with which the rack operates. The rack may be formed as a separate bar secured to the wick casing, and the teeth of the ⁶⁵ bar are supposed to be in the form of spur teeth to engage corresponding teeth on the operating pinion, the arrangement being such that the wick casing and wick may be readily raised and lowered in a true perpendicular direction without danger of the parts binding, and without any tendency of the wick being distorted or pulled more on one side than the other so as to produce an uneven top edge and a consequent ⁷⁰ flame. ⁷⁵

In order to uniformly guide the rack-bar in its up and down movements and to insure this bar not binding in its guide because of any rearward or side strains put upon it by the pinion, or otherwise, I form the vertical side edges of the rack-bar with undercut or other grooves *a*, and I fashion the side walls of the recess, in which the rack-bar slides with flanges or tongues *b*, which are designed to freely enter the side grooves of the rack-bar whereby any inward and side or lateral strain on the bar will be resisted and said bar will be maintained in its true perpendicular position, so that it will not be cramped or subjected to any increased friction, due to distortion, displacement or otherwise, during its movements. By thus normally holding the rack-bar in its true location, its position relatively to the wick, or wick-holder, does not change and hence the wick will be held so as to maintain its top edge true and straight. ⁸⁰ ⁸⁵ ⁹⁰ ⁹⁵

The aforesaid rack is directly engaged by the pinion, 5, and which pinion is suitably fixed to the lower portion of the operating shaft, 7, which carries at its outer end the usual finger wheel, 8, whereby the pinion may be rotated to raise and lower the rack-bar and the wick casing and wick. In the present case I show the shaft as being inclined and consequently the teeth on the rack-bar are inclined so that they may be operatively engaged by the pinion. If the shaft were horizontal the teeth of the rack-bar would likewise be horizontal, but I prefer the inclined shaft as any oil working through from the wick will be prevented from working outwardly on the portion of the shaft engaged by the hand where its presence would be an objection. ¹⁰⁰ ¹⁰⁵ ¹¹⁰ ¹¹⁵ ¹²⁰

The recess or channel in the outer burner tube is open at the top so as to readily register with and admit the lower end of the rack bar, and when the wick is properly seated this opening may be closed by a plug or like part, 9, the inner surface of which will be fashioned to conform to the curvature of the remainder of the tube. ¹²⁵

Projecting from the surface of the outer ¹³⁰

burner tube, 2, are suitable flanges, 10, which form bearings for the shaft 7, the lower end of said shaft being reduced to form a shoulder, 13, to prevent endwise movement of the shaft in one direction and a cross-pin, 14, or like part passing through the reduced end of the shaft to prevent the withdrawal of the shaft in the opposite direction.

10 Mounted on the shaft 7 is a loose sleeve 15, having at one end an annular series of serrations, *e*, and at the opposite end a radial lug, 20, said sleeve being encircled by a helical spring 16, one end of which is fixed to the sleeve while the other end is secured to a pin, 16', on the stationary flange, 10, said flange having a slot or opening, 18, made through it to admit the free end of a spring-plate, 19, which projects sufficiently beyond the flange to be engaged by the lug 20, on the adjacent end of the loose sleeve, said free end of the spring-plate, 19, being disposed over a projection or lug, 21, on the flange, 10, and which lug forms a stop for the spring plate, as I will presently describe.

In order that I may use a positive connection between said sleeve and the shaft, 7, I groove or slot the shaft in the direction of its length and from a point adjacent the serrated end of the sleeve through the outer end of the shaft. The portion of the shaft adjacent the serrated end of the sleeve I notch to form the inclined wall, *d*, and in the slot or groove which is formed longitudinally of the shaft, I slidably mount a plate, *e*, the outer end of which extends through the outer end of the shaft to a point sufficiently beyond the outer surface of the finger wheel to allow said plate to be slid longitudinally of the shaft; to facilitate this action the outer end of the sliding plate may be provided with a knob or like engaging element. The position of the knob, in or out, will also serve as a visual indicator of the condition of the interengaging features at the opposite end. The inner end of the sliding plate passes through a radial slot *g*' formed in a collar *g* which is fast on the shaft, 7, said plate having an inclined surface, *f*, which is designed to engage the outer wall of said slot so that when the plate is pushed inwardly of the shaft, the incline, *f*, on the plate will ride in contact with the wall of the slot and the inner or lower end of the plate will be forced downwardly to allow a spur or tooth, *h*, on the inner end of the plate to ride down the incline, *d*, or wall and bring a small pawl or projection, *i* on said plate into engagement with one of the serrations of the annular series with which the loose sleeve, 15, is supplied, thus locking the sleeve to the plate, *e*, and shaft, 7, so that upon partially rotating the shaft in one

direction through the medium of the finger wheel 8, the sleeve will be rotated, and the lug 20, on the sleeve will be moved until it engages the free end of the spring plate, 19, and carries the same across the width 70 of the slot, 18, and until the further movement of the free end of the spring plate is checked by the lug 21, the extent of movement of this free end of the spring plate, 19 substantially determining the extent of 75 rotation of the shaft to the right, and the consequent upward movement which is given the wick. During this rotation of the sleeve 15 the spring 16 will be wound to a very slight extent. The pinion, 5, and 80 the flanges 10, at each side thereof, as well as the lower end of the shaft, 7, are encased in a housing, 25', of suitable form and description as is customary in burners of this type and as disclosed in my aforesaid prior 85 patents.

In operating the device the sliding plate *e* is withdrawn from engagement with the loose sleeve 15, and the wick with its casing is inserted between the burner tubes with 90 the lower end of the rack-bar, 6, in register with the open top of the slot or recess, 3, in the side of the outer tube. As the walls of this slot or recess and the adjacent side walls of the rack-bar are specially formed 95 with engaging tongue-and-grooves, these latter form an accurate guide for the wick during its insertion and when seating it in the tube, as well as during the up and down adjustment of the wick after the same has 100 been fully seated. As soon as the lower end of the inserted rack-bar arrives opposite the spur wheel it will engage the teeth of the latter and rotation of the shaft, 7, to the left will then lower the wick casing and 105 wick to the desired position; it being understood that the shaft, 7, may be freely turned to the left or downwardly since the shaft is not coupled to the loose sleeve 15.

In adjusting the wick the shaft and loose sleeve are disengaged and the shaft, 7, is rotated to the right to bring the top edge of the wick even with the top of the burner tube. The sliding plate *e*, is then pushed inwardly along the shaft, 7, until its pawl-end, *i*, engages one of the serrations in the periphery of the sleeve, thus locking the sleeve to the shaft. Thereafter to set the wick at the proper distance for burning the shaft 7 is turned to the right or upwardly until the lug 20 of the sleeve is brought into contact with the adjacent free end of the spring plate and depressing said spring plate until it comes against the stop lug 21 will thereby arrest the further rotation of the shaft and stop the operation of the wick-raising elements, fixing the position of the top edge of the wick at such point that the desired blue flame is attained and maintained. The wick will remain in 130

this position, since the helical spring 16 is light and the range of movement of the lug 20 so slight that no appreciable tension is placed upon the spring by the upward movement of the wick. When the wick is to be extinguished, the shaft 7 is turned to the left, and being free to move to the extent of a full revolution, will cause the wick to recede into the burner, extinguishing the flame, where it may remain, or be moved back to burning position. During this movement the helical spring 16 is placed under slight tension, but insufficient to cause a return upward movement of the wick. When the wick is again moved upwardly in position to be lighted, the lug 20 will abut the stop 21 as before and prevent further upward movement of the wick, insuring that the latter will again be raised only to proper burning distance.

When the wick has burned down to the desired extent and must be re-adjusted, the plate *e* is released from engagement with the sleeve 15 and the wick is trimmed and again adjusted flush with the top of the burner tube, the plate and sleeve are again connected, and the parts are operated as before.

The helical spring 16 is used to cause a return of the loose sleeve 15 to normal position when the sleeve is released from connection with the shaft 7, as in setting the wick and inserting or removing the wick, so that the sleeve will be positioned to move to the right only the distance of the opening 18 when it is again connected to the shaft.

The foregoing mechanism provides a simple means for limiting the wick raising function to only a short distance in one direction for burning purposes and provides for a more extended wick lowering action in the other direction. Such an arrangement enables me to so control the flame as to obtain the best heating results, and it provides for the free and substantially frictionless sliding motion of the rack which raises and lowers the wick casing and wick.

Having thus described my invention what I claim as new and desire to secure by Letters Patent is:

1. In an oil burner, the combination of a burner tube, a wick-holder, a rack-and-pinion for operating the holder, means for operating the pinion, wick-controlling means having the capacity of positively stopping the elevation of the wick during a complete movement thereof in one direction so as to set the wick at a fixed and predetermined maximum height above the top of the burner tube, and for returning the wick to said predetermined height after movement in the opposite direction, said wick-controlling means comprising a shaft, a sleeve loose thereon and provided with a lug, a resilient member interposed in the path of movement

of said lug and movable thereby, a stop for said member adapted to limit its movement, and a sliding member on the shaft adapted to engage and disengage the sleeve to thereby connect and disconnect the latter to the shaft.

2. In an oil burner, the combination of a burner tube, a wick-holder, a rack-and-pinion for operating the holder, means for operating the pinion, wick-controlling means having the capacity of positively stopping the elevation of the wick during a complete movement thereof in one direction so as to set the wick at a fixed and predetermined maximum height above the top of the burner tube, and for resetting the wick to said predetermined height after movement in the opposite direction, said wick-controlling means comprising a shaft, a sleeve loose thereon and provided with a lug, a resilient member interposed in the path of movement of said lug and movable thereby, a stop for said member adapted to limit its movement, and a sliding member on the shaft adapted to engage and disengage the sleeve from the shaft, said sleeve having an annular series of serrations, and said sliding member having a projection adapted to engage said serrations.

3. In an oil burner, the combination of a burner tube, a wick-holder, a rack-and-pinion for operating the holder, means for operating the pinion, wick-controlling means having the capacity of positively stopping the elevation of the wick during a complete movement thereof in one direction so as to set the wick at a fixed and predetermined maximum height above the top of the burner tube, and for resetting the wick at said predetermined height after movement in the opposite direction, said wick-controlling means comprising a shaft, a sleeve loose thereon and provided with a lug, a resilient member interposed in the path of movement of said lug and movable thereby, a stop for said member adapted to limit its movement, and a sliding member on the shaft adapted to engage and disengage the sleeve to thereby connect and disconnect the latter to the shaft, said sleeve having an annular series of serrations and said slideable member having a projection to engage the serrations, and having a spur or tooth with an inclined surface, said shaft being notched and the notch having an inclined surface for sliding engagement with said spur and adapted to move the projection radially into and out of engagement with said serrations.

4. In an oil burner, the combination of a burner tube, a wick-holder, a rack-and-pinion for operating the holder, means for operating the pinion, wick-controlling means having the capacity of positively stopping the elevation of the wick during a complete movement thereof in one direction so as to

- set the wick at a fixed and predetermined maximum height above the top of the burner tube, and for resetting the wick at said predetermined height after movement 5 in the opposite direction, said means comprising a sleeve normally loose on the shaft and having a lug, means for connecting the sleeve to the shaft and disconnecting it therefrom, a spring having one end connected to the sleeve and placed under tension when the sleeve is turned in one direction, and adapted to return the sleeve to normal position when movement of said sleeve ceases and the sleeve is released, and means 10 in the path of and co-acting with the lug on the sleeve for limiting the elevation of the wick relatively to the burner tube.
5. In an oil burner, the combination of a burner tube, a wick-holder, a rack-and-pinion for operating the holder, means for operating the pinion, wick-controlling means 15 having the capacity of positively stopping the elevation of the wick during a complete movement thereof in one direction so as to set the wick at a fixed and predetermined maximum height above the top of the burner tube, and for resetting the wick at said predetermined height after movement 20 in the opposite direction, said means comprising a sleeve normally loose on the shaft, and having a lug, a sliding member on the shaft extending beyond the outer end thereof and having an inner end to engage the sleeve and thereby connect the same to the shaft, a spring connected to the sleeve 25 adapted to position the lug thereof relatively to said wick controlling means, a resilient member adapted to be engaged by said lug, and a stop lug for fixing the extent of movement of the resilient member 30 and thereby fixing the elevation of the wick relatively to the top of the burner tube.
- 20

In testimony whereof I affix my signature.

HENRY W. BRENT.
